Primary Examiner — T Chase Nelson(74) *Attorney, Agent, or Firm* — Banner & Witcoff, Ltd.**(57) CLAIM**

The ornamental design for a shoe, as shown and described.

DESCRIPTION

FIG. 1 is a front perspective view of a shoe showing my new design;

FIG. 2 is a bottom view thereof; and,

FIG. 3 is a rear perspective view thereof.

The broken lines depicting the remainder of the shoe show features that form no part of the claimed design.
